UNITED STATES PATENT OFFICE.

SCHAMU M. MOSCHCOWITZ, OF NEW YORK, N. Y.

SPOOL-HOLDER.

SPECIFICATION forming part of Letters Patent No. 268,712, dated December 5, 1882.

Application filed September 4, 1882. (No model.)

To all whom it may concern:

Be it known that I, SCHAMU M. MOSCHCOWITZ, a citizen of the United States, residing at New York, in the county and State of New York, have invented new and useful Improvements in Spool-Holders, of which the following is a specification.

My invention relates to a device intended to hold spools of cotton, silk, and other thread, twine, and similar materials; and the objects sought to be secured are that the holder shall be adapted to protect the thread from dirt and dust, exposing only a sufficient surface thereof to show its color, to prevent the unwinding of the thread, except when intentionally drawn from the spool, to automatically adjust itself to spools of varied sizes, to indicate the number or size of the thread therein, and by its appliances to furnish means for its suspension and for the storage of needles; and with these objects in view my invention consists in a spool-holder provided with independent heads or end pieces and elastic sides or walls, whereby it automatically bodily grasps and adjusts itself to the size of the spool therein contained, and produces a tension which prevents unintentional unwinding of the thread; and my invention further consists in other features of construction, hereinafter described, and specifically set forth in the claims.

Referring to the drawings, Figure 1 is a side elevation. Figs. 2 an 3 are perspectives; Fig. 4, a front view; Fig. 5, an end view, and Fig. 6 a detail of a spool-holder constructed in accordance with my invention.

Like letters refer to like parts in all the figures.

The body portion of the holder consists of a piece of elastic or tempered metal or other suitable substance bent to form a central tube or half-tube, B, and two clasping-walls, A A, curved into a substantially tubular form, and having their end edges bent slightly outward, as clearly shown in the end view. If desired, the tube and half-tube may be conjointly used by securing the latter upon or at either side of the former. In the tube B there is at its lower end a screw-threaded plug, b, and in the upper end thereof I introduce a secondary tube or stopper, b', (see Fig. 6,) which is slotted, as at b², to form two spring-tongues, b³ b³, which

stand normally outside of the peripheral plane of the tube, so as to press against the inner surface of the tube B to retain the stopper therein. By this construction there is provided a suitable receptacle for needles, and the holder proper is adapted, by removing the stopper and the plug, to be supported upon the usual spool-post of a sewing-machine. As thus far described, it will be seen that by separating the free edges of the body portion of the holder a spool of thread or silk can be placed therein and securely held from turning, and thus unwinding the thread, as is the case when, without first securing the end of the thread in the usual notch cut in the spool-flange, the spool is carelessly thrown upon a table and allowed to roll.

In Figs. 2 to 5, inclusive, I have illustrated the holder adapted to be suspended, and to protect the ends of the spool contained therein, and, further, to indicate the size of the thread. A wire, C, is coiled in a horizontal plane to form one head, c', and is projected centrally therefrom and bent to form a hook, c, while the exterior coil is bent at a right angle to the head c', and is secured in the tube, or, as it may be, and preferably is in this instance, a half-tube, B, and at the opposite end of the tube is again bent at c² at a right angle and inwardly, where it may again be coiled to form another head, or, as in this instance, said head is formed of a separate disk of metal or other suitable material secured thereto, as shown at c³.

To indicate the size of thread in the holder the body portion is impressed with or bears indicating-marks a, which are identical with similar marks used in the trade to distinguish threads of different fineness or material. As silk is generally lettered the holder bears the letters A, B, C, D, O, OO, and as thread of other materials is numbered by multiples of 10—as 50, 60, 70, &c.—I provide the initial digit of a number on one of the heads, as shown, whereby the inclosed thread is indicated as to fineness, and by means of the space between the two ends of the body portion sufficient thread is exposed to clearly show its color.

It will be seen that between the indicating-marks a a series of holes, a², are formed. When a spool is inserted into a holder, one should be

selected bearing on its end plate the proper mark, and the free end of the thread should be passed through a hole adjacent to the proper mark on the body, and then the spool should be forced within the holder, when the clamping sections A A will securely retain the spool therein.

It will also be noticed that the coil c' may be formed so as to press upon the end of the contained spool, and in this manner produce the desired friction thereon.

It is evident that the suspension-hook c may be attached at another portion of the holder than that shown, and that other than solid walls may be provided, and by their inherent elasticity clasp directly varied sizes of spools, without a material departure from the gist of my invention, and that the tube or half-tube B may be omitted, if desired.

20 What I claim, and desire to secure by Letters Patent, is—

1. A spool-holder comprising independent head or end pieces and elastic walls arranged to clasp the spool and prevent the same from 25 rolling therein, substantially as shown and described.

2. A spool-holder having elastic walls and an adjacent needle-holder, substantially as shown and described.

3. A stopper for a needle-holder, comprising 30 a tube slotted to form projecting spring-tongues, substantially as shown and described.

4. The combination of a spool-holder and a tube having a removable plug and a stopper 35 provided with projecting spring-tongues, substantially as shown and described.

5. A spool-holder comprising elastic walls having a series of perforations and bearing adjacent indicating-marks, substantially as 40 shown and described.

6. A spool-holder having elastic walls and an end disk bearing indicating-marks corresponding with each other, substantially as 45 shown and described.

7. A spool-holder consisting of elastic walls 50 arranged to clasp a spool bodily to cover the same, except at a portion exposed to show the color of the thread thereon, and provided with a suspension-hook and indicating-marks to show the quality of the contained thread, substantially as shown and described.

In testimony whereof I have hereunto set my hand in the presence of two subscribing witnesses.

SCHAMU M. MOSCHCOWITZ.
